STARTER FOR LOW-POTENTIAL FLUORESCENT TUBULAR LAMPS

Fritz Knobel, Ennenda, Glarus, Switzerland

Application December 3, 1953, Serial No. 395,975

13 Claims. (Cl. 315—100)

The present invention relates to a starter for a low-potential fluorescent tube with series reactors or chokes, of the type in which a rest contact is connected in series with the two electrodes of the tube, and in which a free hanging heat responsive wire cooperates with the arm of an actuating lever acting, upon passage of current through the heat responsive wire, on the movable portion of the rest contact so as to open the latter and to cause, in combination with the choke and with a condenser connected between the two electrodes, arcing of the fluorescent tube, an additional resistance being connected in series with the heat responsive wire, which resistance is short circuited when the rest contact is opened, so as to accelerate this opening by a sudden increase of the current through the heat responsive wire.

Now such starters may under certain circumstances—e. g. when the fluorescent lamp is old and worn-out, or when it is defective, when the ambient temperature is unusually low, or at excessive under-voltage in the mains—not work satisfactorily so that the lamp is not lighted. The lamp flickers, i. e. it flashes at each interruption of the current and no continuous current flow corresponding to the one in a normally working lamp, is attained. If this flickering lasts the contacts, the heat responsive wire and the starting condenser are overworked resulting in a reduced reliability of service of the starter.

According to the present invention this disadvantage is overcome by a bimetal strip secured to the movable portion of the rest contact, and cooperating with a catch provided at the casing of the starter in such a way that the heating of the rest contact occurring at flickering operation causes the bimetal strip to bend and to engage the catch so that the rest contact remains open.

Thus at flickering operation the starter is automatically switched-off so that damages or overworking of the parts of the latter are effectively prevented.

The time for starting a starting device of the above type depends mainly of the heat responsive properties of the heat responsive wire. For constructional reasons, however, it is not possible to increase at will this heat responsive properties, so that in many cases it is necessary to artificially increase the cathode heating current in order to supply the cathode with sufficient heating energy during the relatively short heating time. This artificial increase of the cathode heating current during the heating period could for example be obtained by an opposing winding as described in Swiss Patent 265,338. However, such opposing winding complicates the connection and, moreover, such extremely high cathode heating currents have several disadvantages resulting in their use being limited to the cases in which a very short starting time is desired.

It is therefore a further object of the present invention to provide a starter of the above-mentioned type, in which the additional resistance is formed of a conductor having a negative temperature coefficient in order to increase the starting time of the starter.

If the mass of this conductor with negative tempera-

2

ture coefficient would be chosen as great as would be necessary for the continuous load present, the switch retardation would be too great for the present purpose. Preferably the mass of the conductor with negative temperature coefficient is chosen smaller as it would be necessary for its continuous load, in order to obtain, as the conductor with negative temperature coefficient is short-circuited, a desired switch retardation. Simultaneously it is attained by short-circuiting the said conductor, that the latter is put out of circuit at continuous service and does not produce losses, as it would be the case if a conductor with negative temperature coefficient would be continuously connected in series with the heat responsive wire for increasing the switch retardation.

Other objects and advantages of the invention will become apparent from the description now to follow, of preferred embodiments thereof, given by way of example, and in which reference will be had to the accompanying drawings, in which:

Fig. 1 is a view illustrating a thermal circuit breaker; Fig. 2 is an enlarged fragmentary view of the thermal circuit breaker of Fig. 1;

Fig. 3 is an enlarged fragmentary view similar to the one of Fig. 2, with the circuit-breaker in another working position;

Fig. 4 shows a rest contact;

Fig. 5 is a plan view of the lower portion of the contact of Fig. 4;

Fig. 6 illustrates a modified form of a rest contact;

Fig. 7 shows the wiring scheme of the whole starter;

Fig. 8 is a fragmentary view of a modified form of a thermal circuit-breaker; and

Fig. 9 represents the wiring scheme of a modified form of a starter of a low-potential fluorescent tubular lamp.

In Fig. 1 reference numeral 1 designates a casing made of insulating material and to which are secured the stationary portion 2 and the movable portion 3 of a rest contact or starter switch and the connecting lugs 4 and 5 associated therewith. An arm 6 and a pivot 7 are connected with connecting lugs 8 and 9. Rotatably mounted on pivot 7 is a bushing 10 which carries an actuating lever 11. Reference numeral 12 designates a heat responsive wire, which has its one end connected to the arm 6 while its other end is wound around the bushing 10. The additional resistance consists of a loop 37, which is formed by a portion of the heat responsive wire leading from the bushing 10 to the connecting lug 9. Into this loop 37 is connected a conductor B having a negative temperature coefficient. The operation of such a conductor B with negative temperature coefficient will be explained in detail in connection with Fig. 9. A copper wire connection 38 is connected with a contact 39 insulated with respect to the portion 3 of the rest contact. This copper wire connection 38 serves to short-circuit the additional resistance 37 when the rest contact is opened. The heat responsive wire 12 is held strained by a spring 13 acting upon the lever 11.

A bimetal strip 14 is fixed to the movable portion 3 by means of a contact rivet 18 in such a way that in the case of the contact growing warm the heat is transmitted to the bimetal strip 14 and causes the latter to bend in the direction indicated by the arrow in Fig. 2. The bimetal strip 14 cooperates with a catch 15 provided with a hook 16 and secured in the groove 17 of the casing 1 by means of a suitable adhesive such as for example synthetic resin. This catch 15 may be of bimetal too, so that at variation of the ambient temperature from —25° C. up to 100° C. it bends in the same direction and to the same extent as strip 14, as clearly visible in Fig. 2.

As may be seen from the wiring scheme of Fig. 7 the heat responsive wire 12 is connected to some turns of the choke 25. Moreover the rest contact 2, 3 is connected

between the heating electrodes 28, 29 of the lamp 27, i. e. it is connected in series with the choke 25 to the mains 32, 33. Reference numeral 24 designates a condenser connected between the electrodes 28, 29. The rest contact 2, 3 may be bridged by a contact 23.

The operation of the described starter is the following:

If, for example, an alternating potential of 220 v. is switched on the terminals 32 and 33, a current flows from the terminal 32 through the choke 25, the lamp electrode 28, the lug 5, the closed rest contact 2, 3, the lug 4, the lamp electrode 29 and back to the second mains terminal 33. Simultaneously a current is induced in the choke windings lying between the lugs 8 and 9, which current flows from lug 8 to the arm 6 through the heat responsive wire 12, bushing 10, pivot 7 and to the lug 9. The heat responsive wire 12 is heated by this current flowing through it and expands itself so that the lever 11 moves downwardly in direction of the arrow in Fig. 1 under the action of the spring 13 and removes the portion 3 of the rest contact, electrically connected with the lug 5, from the stationary portion 2 of the rest contact, electrically connected with the lug 4. The opening of the contacts 18 causes a sudden interruption of the current and a high induction voltage in the choke 25, which normally is sufficient for arcing the fluorescent tubular lamp 27, the electrodes 28 and 29 of which have been heated by the preceding current flow to a temperature of approximately 600° C. Now it may occur that even with intact electrodes 28, 29 and in spite of a high induction voltage the lamp 27 is not lighted. The reasons therefor may be of various origins such as worn-out old or defective lamps, unusually low ambient temperature, excessive under-voltage in the mains etc. In such a case the starter of the lamp tries without success to light the lamp by continually opening and closing the contacts 18. This leads to the so-called "flickering" of the lamp, as the latter flashes at each current interruption owing to the high induction voltage, while no continuous current flow according to the one in a normally working lamp is attained. If such a flickering lasts for a longer time the contacts 18, the heat responsive wire 12 and the condenser 24 of the described starter are heavily overworked resulting in the reliability of service of the starter being substantially reduced. This drawback is avoided in the afore-described starter as the heating of the rest contact causes the bimetal strip 14 to bend in direction of the arrow, whereby, as this bending has attained a certain extent, the bimetal strip will engage the catch 15 and be retained by the hook 16 of the latter as shown in Fig. 3 to maintain the contact parts 2, 3 of the starter switch separated. The dimensions of the parts 14 and 15 are such that the distance between the contact elements 18 is about 5 mm.

As may be seen from Figs. 4 and 5 the movable portion 3 of the rest contact may be provided with an elongated slot 20, which reduces the heat transmission to the rear portion of the portion 3 so that a quicker heating of the bimetal strip 14 is attained.

In the modified form shown in Fig. 6 the portion 3 of the rest contact is shortened and the bimetal strip 14 is secured to it by a rivet 19 while the contact 18 is only riveted to the bimetal strip 14 so that the whole heat of the contact is immediately transmitted to the strip 14 and a quick and strong bending is attained.

Of course, the locked starter must, subsequent to repair of the lamp, be brought back into its normal working position. This could be obtained very easily by a mechanical release device, however, as such starters are normally built together with the choke 25 they are not accessible without else so that such a device would not be satisfactory. A more satisfactory solution of this problem is shown in Fig. 7 in which an electrical restoring contact 23 which may be a push-button switch known per se is arranged on the switch-board and connected with the lugs 4 and 5. If subsequent to the repair of the de-

fective lamp and to the switching-in of the mains 32, 33 the contact 23 is short-circuited, which in fact corresponds to a bridging of the open contacts 18, the normal pre-heating current flows again through the lamp 27 and through the choke 25. The heat responsive wire 12 is again heated and the lever 11 moves in the direction indicated by the arrow to the maximum opening position of the contact, in which position the opening is larger than it is in the locked position shown in Fig. 3. The bimetal strip 14, which has rapidly adapted itself to the ambient temperature and therefore exerts a releasing force upon the hook 16, is released in the very moment in which the opening of the contact is such as to permit for the hook 16 to return into its starting position. The starter is now again in its normal working condition.

In the modified form according to Fig. 8 such a restoring contact is provided on the casing 1 of the starter. The contact spring 21 has its one end connected to the lug 4 and its other end provided with a contact rivet 22 adapted to cooperate with a similar contact rivet 22 at the lug 5. The contacts 22 are closed for restoring the locked starter by means of a button provided on the contact spring 21.

As stated before with respect to Fig. 1, the additional resistance 37 may comprise a conductor B with negative temperature coefficient. Fig. 9 now represents the wiring scheme of a modified form of a starter for a low-potential fluorescent tubular lamp R in which the additional resistance is such a conductor with negative temperature coefficient.

The wiring scheme represented in Figure 9 of a starter of a low-potential fluorescent tube R comprises a circuit coming from a main circuit wire P over a main switch C, a choke D, a cathode K₁, a rest contact a₂, a cathode K₂ and back to the main circuit wire O. A conductor B with negative temperature coefficient, which may be short-circuited by a contact a₁, and a heat responsive wire A are connected in series to some turns of the choke D. The wiring scheme of Fig. 9 contains parts which are shown in Fig. 1. The heat responsive wire A of this scheme corresponds to the heat responsive wire 12 of Fig. 1. Further the contact a₁ corresponds to the contacts 11, 39 of Fig. 1 and the contact a₂ corresponds to the contacts 2, 18 of Fig. 1. As the heat responsive wire A grows warm its heat expansion firstly closes, by means of an actuating lever an auxiliary contact a₁ and then opens the rest contact a₂, which, in known way per se, owing to the quick interruption of current, causes an induction voltage at the choke D and thereby starts the arcing of the fluorescent tube. The actuating lever mentioned above may be lever 11 of Fig. 1 which operates the contacts a₁ and a₂ of Fig. 9. When the heat responsive wire A of Fig. 9, or 12 of Fig. 1 actuates by heat expansion, the lever 11 then closes first the auxiliary contact a₁ of Fig. 9, or 2, 18 of Fig. 1.

In this wiring scheme the additional resistance used is not an ohmic resistance with neglectable temperature coefficient but a conductor B having a great negative temperature coefficient, as for example dioxide of uranium, copper oxide, manganese oxide, nickel oxide, etc. The conductor B having when cold a resistance which is approximately 5 to 20 times superior to its resistance when warm, the initial current through the heat responsive wire A is limited to such a small value that the latter is practically not heated and therefore does not expand itself. On the other hand this current suffices for heating up the relatively small mass of the conductor B. Owing to this warming the resistance of the conductor is reduced and the current increases resulting into increasing temperature of the conductor B and further reduction of its resistance etc. The greater current now also results in a heating up and expanding of the heat responsive wire A, so that after a determined switch retardation the auxiliary contact a₁ is closed and thus the conductor B is short-circuited. Moreover, as already mentioned, the

arching of the fluorescent tube is started by opening of the rest contact. Owing to the fact that the conductor B is short-circuited it is not necessary for it to have a mass chosen for continuous load. This mass may on the contrary be much smaller and adapted to the desired switch retardation.

I claim:

1. In a starter for a low-potential fluorescent lamp having a pair of electrodes, a casing of insulated material, contacts for conducting current to said electrodes and through at least one of the electrodes, a heat responsive wire connected in series to one of said contacts, a starter switch comprising a movable contact portion and a stationary contact portion normally in contact with each other and in series with one of the contacts for one of the electrodes and one of the contacts for the other electrode and responsive to changes in the length of said heat responsive wire, a bimetal strip secured to the movable portion of said starter switch and adapted to bend to open said switch when the starter switch grows warm, and a catch secured to the casing and adapted to cooperate with said bimetal strip upon bending of the latter so as to keep the starter switch open.

2. A starter as set forth in claim 1 wherein the catch is formed of bimetal material, said bimetal strip and said bimetal catch bending in the same direction and to the same extent under the influence of the ambient temperature, and said bimetal catch engaging said bimetal strip upon bending of the latter when the starter switch grows warm.

3. A starter as set forth in claim 2 wherein the movable contact portion of the starter switch is provided with an elongated slot for reducing the heat transmission to the end of this portion opposite said bimetal strip.

4. A starter as set forth in claim 1, wherein said bimetal strip is secured to the movable portion of the starter switch by means of the contact rivet of the latter.

5. A starter as set forth in claim 1, wherein said bimetal strip is secured to the movable portion of the starter switch by means of a separate rivet, and wherein the rivet at the bimetal strip provides for direct heat transfer to the bimetal strip.

6. A starter as set forth in claim 1, wherein the means for securing the catch to the casing comprises an adhesive substance.

7. A starter as set forth in claim 1, including an electrical restoring contact bridging said starter switch and adapted upon actuation to open the movable contact portion of the starter switch to release the bimetal strip out of engagement with the catch.

8. A starter as set forth in claim 1, including a push contact switch adapted to bridge said starter switch for releasing the bimetal strip out of engagement with the catch.

9. A starter as set forth in claim 7, wherein said restoring contact is mounted on the casing.

10. A starter as set forth in claim 1, including a resistance formed of a conductor having a negative temperature coefficient and connected in series with said heat responsive wire and adapted to be short-circuited upon opening of the starter switch.

15 11. A starter as set forth in claim 10 wherein the mass of said additional resistance having a negative temperature coefficient is adapted to the desired switch retardation and is smaller than it would be necessary for continuous load.

12. A low-potential fluorescent lamp comprising in combination, a series choke, a tube having a pair of tube electrodes, a casing of insulating material, a heat responsive wire mounted in said casing and connected in series with said electrodes, a starter switch comprising a movable and a stationary portion connected in series with said electrodes and responsive to changes in the length of said heat responsive wire, a bimetal strip secured to the movable portion of said starter switch and adapted to bend when the starter switch grows warm, a catch secured to said casing and adapted to cooperate with said bimetal strip upon bending of the latter so as to keep the starter switch open, and an additional resistance adapted to be short-circuited upon opening of the starter switch, said additional resistance being formed of a conductor having a negative temperature coefficient.

20 13. A low-potential fluorescent lamp as defined in claim 12 wherein the movable portion of the starter switch is provided with an elongated slot to reduce heat transmission to the end of this portion opposite said bimetal strip, and wherein the catch is formed of bimetal material, said bimetal strip and said bimetal catch bending in the same direction and to the same extent under the influence of the ambient temperature, and said bimetal catch engaging said bimetal strip upon bending of the latter when the starter switch grows warm.

25 14. A low-potential fluorescent lamp as defined in claim 12 wherein the movable portion of the starter switch is provided with an elongated slot to reduce heat transmission to the end of this portion opposite said bimetal strip, and wherein the catch is formed of bimetal material, said bimetal strip and said bimetal catch bending in the same direction and to the same extent under the influence of the ambient temperature, and said bimetal catch engaging said bimetal strip upon bending of the latter when the starter switch grows warm.
